INVENTOR:

G. Bennion

UNITED STATES PATENT OFFICE.

CHARLES BENNION, OF LEICESTER, ENGLAND, ASSIGNOR TO UNITED SHOE MACHINERY COMPANY, OF PATERSON, NEW JERSEY, A CORPORATION OF NEW JERSEY.

MACHINE FOR USE IN THE MANUFACTURE OF BOOTS AND SHOES.

1,092,470.

Specification of Letters Patent.

Patented Apr. 7, 1914.

Application filed September 19, 1908. Serial No. 453,804.

To all whom it may concern:

Be it known that I, CHARLES BENNION, a subject of the King of England, residing at Leicester, in the county of Leicester, England, have invented certain Improvements in Machines for Use in the Manufacture of Boots and Shoes, of which the following description, in connection with the accompanying drawings, is a specification, like reference characters on the drawings indicating like parts in the several figures.

This invention relates to machines for use in the manufacture of boots and shoes and more particularly to machines for shaping the bottoms or other portions of a shoe.

A particular object of the invention is to provide an improved machine for beating and otherwise shaping the bottom of a lasted shoe to even and compact the upper stock thereon for forming a suitable surface upon which to lay the outersole.

An important feature of this invention consists in the provision in a tool having beating devices that are movably mounted in a rotary carrier and are held outward by centrifugal force, of means for guiding or determining the direction of movement of the beating devices under the action of centrifugal force and reversely under the pressure of the work against the acting faces of the beating devices.

As shown in one construction herein the beating devices are movable in a right line from and toward the axis of the carrier and in an approximately radial direction. The path may, however, be varied within this invention to give any predetermined movement that may be desired, as, for example, to give a movement oblique to the diameter and slightly curved as shown in a further construction. This path permits the beating devices to hang upon the stock as they strike it and then, as they advance over it, to exert a greater drawing action for forcing the stock inwardly than is provided by the radial guideways.

In the illustrated embodiment of the invention the beating devices comprise one roll or a plurality of adjacent rolls or rings arranged to turn freely upon an axle or rod which is movably held in the hub or end disks of the carrier and guided in radial slots therein. When the tool is rapidly rotated, as, for example, at about 2060 revolu-

lutions per minute which appears from experiments to give the best results, the beating devices are automatically forced outwardly in the guide slots and as they contact with the work the beating devices turn upon their axles to give a rolling blow to the stock and yield inwardly toward the axis in a direction determined by the guide slots to give an elastic quality to the blow.

A further feature of this invention consists in providing means for holding the beating devices normally in a predetermined position with relation to the limits of their radial movement. This means is shown as comprising yielding devices coöperating with the end disks or hubs and the rods or axles to hold the beating devices normally at the outer limits of their movement. This arrangement maintains the normal cylindrical form of the roll as a whole when it is at rest. The yielding devices also serve

70 another purpose in that they form a constant force holding the beating devices outward on the roll. This force is augmented by centrifugal force when the roll is in motion, the extent of the centrifugal force varying of course with the speed at which the roll is driven. This speed can be changed according to the kind of work to be done and the quality of blow that is desired.

With this construction it is not necessary to 85 maintain a high speed in order to get enough outward pressure on the beating devices to cause them to strike sharp blows upon the work as might be necessary with light beating devices if centrifugal force alone were relied upon to hold the beating devices outward in their guides. The

80 springs prevent the beating devices from rebounding as they strike the stock and thus releasing their effective contact with the 90 stock as they pass over it. This is particularly important when the guideways for the beating devices are inclined backwardly relative to the direction of rotation for the springs insure that the beating devices will 95 grip and hang upon the stock as they advance over it and thus effect a drawing or pulling action in the direction of their rotation which is desirable for working the upper inwardly from the edge of the last.

100 105 These and other features of the invention, including certain details of construction and combination of parts will appear in

connection with the following description of a preferred construction embodying the invention and will then be pointed out in the claims.

5 Figure 1 is an end elevation partly in section. Fig. 2 is a side view also partly in section. Figs. 3 and 4 illustrate a slight modification.

10 The machine of which only the driving shaft 2 for actuating the beating roll is herein shown, may be arranged to rest upon a bench or be supported on a post. The roll comprises a carrier or hub 4 having end plates or disks 5 having formed in their edges guideways 6, to receive guide blocks 8 which are free to slide therein. The guideways may be arranged as shown in Fig. 1 to extend obliquely with relation to the diameter of the roll, or diametric lines 15 thereon, to permit the beating devices guided thereby to move inwardly and backwardly with relation to the direction of rotation of the roll. Preferably the guideways will be curved slightly as shown in Fig. 1 although they may be straight. It is also within this invention to form the guideways on radial lines of the hub as shown in Fig. 3. The guide blocks receive axles or rods 10 which are thus supported for either end to yield 20 independently of or to a different extent from the other. The beating devices which are mounted on the axles 10 are shown as rolls 12 free to turn on their axles. Such beating device may comprise a single roll 25 as shown in Fig. 2 or a plurality of adjacent rolls as shown in Fig. 4. The guideways 6 preferably contain springs 14 arranged to hold the blocks 8 and the beating devices 12 normally outwardly to the limits of their 30 movement but yield under pressure of the work against the acting faces of the beating devices. The springs maintain the beating devices in a circular series when the roll is at rest or running slowly. An annular plate 35 on the outer face of each disk 5 has an inwardly turned lip which plate and lip confine the blocks 8 in the guideways 6.

40 In the use of the apparatus the tools will be impelled outwardly by centrifugal force and a shoe may be presented as indicated in Fig. 1 in position for the beating devices to strike the surface which is to be treated. If it is a lasted shoe the bottom of which is to be compacted and evened to form a suitable surface to receive the outersole the shoe 45 may be so held that the overworked marginal portion of the upper material on the innersole will be beaten downwardly and, preferably, inwardly from the edge of the 50 shoe. The arrangement of the guideways by which the beating devices yield backwardly and inwardly permits said devices to hang to the upper as they pass over it and thus increases the inward pull or draft on the upper being treated. The use of the 55

60 springs reinforces the action of centrifugal force and assists in causing the beating devices to hang to the stock and maintain their pressure thereon as they advance over it instead of rebounding. The beating devices 70 preferably have rolling contact with the stock so that there is little liability of their marring it as might occur if they were merely rubbing tools.

Having explained the nature of this invention and described a preferred construction embodying the same, I claim as new and desire to secure by Letters Patent of the United States:—

1. A shoe shaping machine comprising a 80 rotary tool having beating devices movably mounted thereon and arranged to be moved outwardly by centrifugal force when the tool is in motion and having means for guiding and controlling the direction of the 85 movement of the beating devices under the action of centrifugal force and their reverse movement under the pressure of the work against the acting faces of the beating devices, said beating devices being normally 90 idle but free to roll on the work as they rub over it.

2. In a shoe shaping machine, in combination, a rotary carrier, shoe beating devices comprising normally idle work-engaging 95 members adapted to act by impact upon the stock to be treated and then by rolling pressure as they are drawn over the stock by the movement of the rotary carrier, supports for said work-engaging members movable in the carrier under the action of centrifugal force when the carrier is actuated and guiding means for determining the direction of said movement.

3. A shoe shaping machine having, in 105 combination, a rotary carrier, beating devices movable therein under the action of centrifugal force when the carrier is actuated, said beating devices being normally 110 idle but mounted to have independent rolling contact with the stock being operated upon, and guideways formed in the carrier to control the direction and extent of the movement of the beating devices therein.

4. A shoe shaping machine having, in 115 combination, a rotary carrier comprising end disks having outwardly extending guideways, guide blocks slidably mounted in said guideways, axles supported in said blocks and beating devices carried by the 120 axles, the said beating devices normally having no axial movement but mounted to be free to turn about their axes as they progress over the work.

5. A shoe shaping machine having, in 125 combination, a rotary carrier comprising end disks having outwardly extending guideways, guide blocks slidably mounted in said guideways, axles supported in said blocks, beating devices carried by the axles, 130

and yielding means for holding the guide blocks at one end of said guideways, the said beating devices normally having no axial movement but mounted to be free to turn about their axes as they progress over the work.

6. A shoe shaping machine having, in combination, a rotary carrier, beating devices movable therein under the action of centrifugal force when the carrier is actuated, and means arranged to exert upon the beating devices, in the direction in which the centrifugal force acts a light pressure merely sufficient to hold the beating devices in their normal positions when the carrier is at rest.

7. A shoe shaping machine having, in combination, a rotary carrier, beating devices movable therein under the action of centrifugal force when the carrier is actuated, guiding means for determining the direction of said movement of the beating devices, and yielding means for holding the beating devices normally at the outer limits of their movement, said beating devices being normally idle but free to move axially in rolling engagement with the work.

8. A shoe shaping machine having, in combination, suitable actuating means, a rotary carrier operatively connected therewith and comprising end plates having guideways inclined inwardly and backwardly with relation to the direction of rotation, and beating devices mounted upon the carrier and arranged to slide backwardly in said guideways against the action of centrifugal force when they strike the work.

9. A shoe shaping machine having, in combination, suitable actuating means, a rotary carrier operatively connected therewith and comprising end plates having guideways inclined inwardly and backwardly with relation to the direction of rotation, and beating devices mounted upon the carrier and arranged to slide backwardly in said guideways when they strike the work and means for holding the beating devices yieldingly in their outermost positions.

10. In a shoe shaping machine in combination, suitable actuating means, a rotary wheel operatively connected therewith and comprising end members in which are formed guideways inclined backwardly with

relation to the direction of rotation, and shoe beating devices guided in said ways and adapted to hang to the stock when they strike it and to yield backwardly and inwardly in the carrier as they advance over the stock.

11. A shoe shaping machine having, in combination, suitable actuating means and a rotary beater comprising a carrier and a plurality of rolls arranged about the periphery of the carrier and mounted for movement inwardly and outwardly with relation thereto, and also for axial movement as the said rolls progress over the work to force the marginal edges of upper on the bottom of the shoe inwardly from the edges of the shoe bottom, said beater having provision for permitting and guiding in definite paths the movements of the rolls from and toward the periphery of the carrier.

12. A machine of the class described, having, in combination, a rotary carrier comprising a hub provided with end plates, guideways formed in the edges of the end plates, guide blocks yieldingly mounted in the guideways, springs normally holding the guide blocks outwardly, annular flanges on the end plates having inwardly turned lips for confining the guide blocks and limiting their outward movements, and beating members supported at their ends in the guide blocks.

13. A shoe shaping machine having, in combination, a rotary carrier, beating devices movable therein under the action of centrifugal force when the carrier is actuated, said carrier being provided with guideways in which opposite lateral ends of the beating devices are confined, said guideways being formed to control the direction and the extent of movement of the beating devices therein and said beating devices being normally idle but free to turn and roll over the work as they strike the work and rub over it.

In testimony whereof I have signed my name to this specification in the presence of two subscribing witnesses.

CHARLES BENNION.
